UNITED STATES PATENT OFFICE.

WILLIAM F. BRINGE, OF MILWAUKEE, WISCONSIN, ASSIGNOR TO THEODORE LEUBUSHER AND BENJAMIN F. SALZSTEIN, BOTH OF MILWAUKEE, WISCONSIN.

ADVERTISING DEVICE.

1,255,076.

Specification of Letters Patent. Patented Jan. 29, 1918.

Application filed September 30, 1916. Serial No. 123,088.

To all whom it may concern:

Be it known that I, WILLIAM F. BRINGE, a citizen of the United States, residing at Milwaukee, in the county of Milwaukee and State of Wisconsin, have invented a certain new and useful Improvement in Advertising Devices, of which the following is a full, clear, concise, and exact description, reference being had to the accompanying drawings, forming a part of this specification.

My invention relates to advertising and display devices and contemplates a unique placard which can be employed in attractively dressing a show case or show window where it is desired to apply legends to wares for sale or articles on exhibition.

In arranging a window or show case display the use of ordinary placards is generally discouraged since they tend to mar the general attractiveness of a display and its effect as a whole, notwithstanding the fact that from a utilitarian point of view it would be desirable to employ placards.

Ordinary placards can not be well and conveniently applied to the particular articles to which they refer, unless they be so small as to be useless or unless the various wares are too widely spaced apart to use the allotted space economically.

It is the object of my invention to provide a new placard which shall not be subject to the difficulties of the prior art and which shall at once provide a device which may conveniently and attractively be applied directly to an article on display or to a surface upon which the article is laid in such a way as to make its application to the article unmistakable and artistically attractive.

To the ends above pointed out, I provide a placard of cut-out lettering, continuous and of flexible and resilient sheet material, provided with a plurality of supporting spears, whereby the placard itself may be fashioned into any desirable form and, in this form, be held in place by the relative disposition of the spears which thus simultaneously support the placard and maintain it in the particular form selected. The fact that the lettering is cut out increases the flexibility of the device and the possibilities of artistic and economical disposition.

In order that my invention may be more

clearly understood, I shall refer to the accompanying drawings in which—

Figure 1 is an elevational view of my device, showing it applied for instance to the floor board of a show case or display window;

Fig. 2 is a plan view thereof;

Fig. 3 is an end view thereof;

Fig. 4 is a plan view showing the device in connection with a watch on display, as a simple illustration of its capabilities; and

Fig. 5 shows a modified form of construction, in end view.

The placard itself is of cut-out lettering, as illustrated at 6 in Fig. 1, being preferably of that type of lettering which is in and of itself continuous, such as script. This continuous member 6 is of resilient and flexible sheet material, preferably of metal, stamped out, although it could be made of some other suitable material, and in other ways. Extending downwardly from the bottom of the member 6 there are a plurality of pins or spears 7, 7, spaced quite widely apart and secured in place in any convenient manner, for instance, if the member 6 is of metal, by soldering them to the back of the member 6, as illustrated in Figs. 1, 2 and 3.

I have shown the pins or spears 7, 7 to be inserted in the member 8 which may be assumed to be the floor-board of a show case or display window, or a display pedestal or the like. I have illustrated further spears or pins 7^a, 7^a, which may be applied to the member 6, for purposes of certain shaping which may be desired, particularly when the member 6 has considerable length.

Fig. 4 illustrates a simple formation wherein the member 6 has been fashioned into substantially semi-circular form, the spears 7, 7, being inserted in the member 8 with the member 6 so formed. The member 6 is not bent beyond its elastic limit and its resiliency brings it back to planar shape, when the spears are released from the member 8, so that the device can be used again in another form without showing signs of having been previously otherwise formed. While the device is in use in this way, however, the spears 7, 7 support it in upright position and maintain it in desired form, for instance as partially to surround

the watch *w* (Fig. 4) on display, the relative positions of the spears determining the particular extent of the concavity as desired for artistic and economical reasons.

b In Fig. 5 I illustrate a modification which can be employed when the member 6 is made of metal. Here the spear 7' is made integral with the member 6, thus effectively simplifying the manufacture.

10 I claim:—

In an advertising device, a placard mem-

ber of flexible and resilient material, and a plurality of spears secured thereto, said spears being adapted for insertion in a suitable body to support said placard member 15 thereon whereby the placard member between the spears may be flexed in any of a plurality of curves and so held.

In witness whereof, I hereunto subscribe my name this 26th day of September, A. D. 20
1916.

WILLIAM F. BRINGE.
